US00D974038S

(12) **United States Design Patent** (10) **Patent No.:** **US D974,038 S**
(45) **Date of Patent:** **** Jan. 3, 2023**

(54) **EARPHONE CASE**

(71) Applicant: **Logitech Europe S.A.**, Lausanne (CH)

(72) Inventors: **Michael Joseph Roy**, Portland, OR (US); **Victor Manuel Sanchez**, San Jose, CA (US)

(73) Assignee: **LOGITECH EUROPE S.A.**, Lausanne (CH)

(**) Term: **15 Years**

(21) Appl. No.: **29/760,612**

(22) Filed: **Dec. 2, 2020**

(51) LOC (14) Cl. **03-01**

(52) U.S. Cl.

USPC **D3/297**

(58) **Field of Classification Search**

USPC D3/201, 207, 208, 211, 212, 274, 276, D3/294, 295, 297; D9/504, 549

CPC H04R 1/1033

See application file for complete search history.

(57) **CLAIM**

The ornamental design for an earphone case, as shown and described.

DESCRIPTION

FIG. 1 is a top, front, left side perspective view of an earphone case in an open position, showing our new design; FIG. 2 is a top, back, left side perspective view thereof.

FIG. 3 is a bottom, back, right side perspective view thereof; FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a top, front, left side perspective view of the earphone case of FIG. 1 in a closed position;

FIG. 11 is a bottom, back, right side perspective view thereof;

FIG. 12 is a top, back, left side perspective view thereof;

FIG. 13 is a front view thereof;

FIG. 14 is back view thereof;

FIG. 15 is a left side view thereof;

FIG. 16 is a right side view thereof;

FIG. 17 is a top view thereof; and,

FIG. 18 is a bottom view thereof.

The broken lines in the drawings depict portions of the earphone case that form no part of the claimed design.

1 Claim, 16 Drawing Sheets
